UNITED STATES PATENT OFFICE

109,050

DESIGN FOR A COMBINED INNER FOOD RECEPTACLE AND HOLDING FRAME THEREFOR

Beulah Dittmer, Baldwin Park, Calif.

Application September 8, 1937, Serial No. 71,501

Term of patent 14 years

To all whom it may concern:

Be it known that I, Beulah Dittmer, a citizen of the United States, residing at Baldwin Park, in the county of Los Angeles, State of California, have invented a new, original, and ornamental Design for a Combined Inner Food Receptacle and Holding Frame Therefor, of which the following is a specification, reference being had to the accompanying drawing, forming part thereof.

Figure 1 is a perspective view showing the appearance of the inner food receptacle.

Figure 2 is a perspective view showing the ap-

pearance of the holding frame in association with the inner receptacle.

Figure 3 is a perspective view showing a bottom plan view of the holding frame.

The dominant feature of the design resides in the inner food receptacle, as shown.

I claim:

The ornamental design for a combined inner food receptacle and holding frame therefor, substantially as shown and described.

BEULAH DITTMER.
